UNITED STATES PATENT OFFICE.

NATHANIEL CRANK, OF HILL CITY, KANSAS.

DOOR-STOP.

1,357,765.

Specification of Letters Patent.

Patented Nov. 2, 1920.

Application filed January 7, 1920. Serial No. 349,872.

To all whom it may concern:

Be it known that I, NATHANIEL CRANK, a citizen of the United States, and a resident of Hill City, county of Graham, and State 5 of Kansas, have invented a new and Improved Door-Stop, of which the following is a full, clear, and exact description.

This invention relates to door stops and holders. More particularly this invention 10 relates to a door stop or holder to be pivotally fastened on the floor to hold the door in open position.

An object of the invention is to provide a combination door holder and stop capable 15 of holding a door open in any desired position to prevent the premature opening or closing of the door. It is also a purpose to provide a door holder having the facility of being adjustable in width in order to 20 accommodate doors of various thicknesses.

Finally, it is an object with others to provide a door stop and holder comparatively simple in design and construction, inexpensive to manufacture, and one which 25 is unlikely to get out of working order.

The invention has relation to the combination and arrangement of simplified door stop parts as set forth in the appended 30 claims defining the invention, and one particular embodiment of which is described 35 in the following specification and portrayed in the accompanying drawing.

Figure 1 illustrates a plan fragmentary view of the door stop fastened to the floor 35 adjacent the door to hold a door in open position, and Fig. 2 illustrates a side elevation of the door holder, the said view being fragmentary to portray the position of parts, and the door being shown in perspective view.

Figs. 3 and 4 illustrate detailed views of the door stop where each figure details a section taken on the indicated section line of the other figure.

45 A door stop constructed in accordance with the plans of my invention comprises a bracket pivoted on the floor, and a slide related with the bracket to form a receptacle means to hold the door when the stop 50 is pushed into position.

In presenting a more detail description of my invention, there is shown in the drawing a bracket 6, formed of a piece of metal stock with an up-turned end 7. 55 The bracket is preferably constructed of

channel material which provides a guide 8 on one of the brackets. In constructing the bracket it is practical to employ a piece of channel stock, one end of which has the ribs cut therefrom to leave a plane upturned end 7. A screw hole 9 is made in one end of the bracket, and a slot 10 is made in the central portion of the bracket longitudinal with the greater dimension thereof.

60 There is provided a slide which works back and forth in the guide 8 of the bracket 6. This slide comprises an angle plate 12 having a hole formed in one of the sides registering with the slot 10 of the bracket. 70 The angle plate 12 has a face plate 13 fastened to the up-turned side thereof. The parts 7 and 13 may be faced with appropriate padding such as rubber or felt to present a non-abrasive surface to the door 75 when engagement is effected between the door and the stop.

A clamp screw having a thumb-nut 14 is passed through the slot 10 and hole in 80 the angle plate. The thumb-nut may be tightened down to clamp the slide 12 in the guide of the bracket. In this manner the distance between the upturned end 7 of the bracket and the face plate 13 is adjustable 85 to receive a door of any thickness.

The installation of the door stop merely requires the use of a screw or similar holding means. The screw 15 or nail is passed through the hole 9 and anchored to the floor which pivotally secures the door 90 holder in the desired position. A stop, such as the screw 17 is fastened to the floor to limit the pivotal movement of the door stop in one direction. The door holder may be moved inwardly and outwardly about 95 the holding screw 15 by the use of one's foot when the door B is opened. In this manner the door stop may be pushed into engagement with the door as shown in dotted lines in Fig. 1, thereby holding the 100 door against movement in either direction. Likewise the door stop may be pivoted outwardly to free the door by thrusting the bracket away from the door.

The use of this door stop obviates the 105 prevailing trouble and annoyance of slamming doors. It is simple and inexpensive to produce, and requires little effort to install it for use in connection with all types of doors.

Having thus described my invention what I claim as new and desire to secure by Letters Patent is as follows;—

1. A door stop and holder comprising a bracket, an up-turned end formed on the bracket to engage one side of a door, said bracket formed of channeled stock to provide a guide, said bracket having a slot formed longitudinally therein, and a hole 5 made in the bracket to secure same to the floor, an angle plate having a hole which registers with the longitudinal slot and arranged to engage the other side of the door, a clamp screw passed through the slot and 10 through the hole of the angle plate, and provided with a nut to adjustably clamp the angle plate to the bracket in order to accommodate doors of variable thickness.
2. A door stop and holder comprising a bracket, an up-turned end formed on the bracket to engage one side of a door, said bracket formed of channeled stock to provide a guide, said bracket having a slot 15 formed longitudinally therein, and a hole made in the bracket to secure same to the floor, an angle plate having a hole which registers with the longitudinal slot and arranged to engage the other side of the door, a clamp screw passed through the slot and 20 through the hole of the angle plate, and provided with a nut to adjustably clamp the angle plate to the bracket in order to accommodate doors of variable thickness.
3. A door stop or holder to be pivotally fastened on the floor to hold a door in open position or any other desired position to prevent premature opening or closing of the door, comprising a bracket, an upturned 25

part on the bracket, a slide carried on the bracket, and a clamp screw to hold the slide in adjusted position, said slide and upturned part forming an open receptacle means to hold a door, and said bracket being provided with means for pivotally securing it 45 to the floor.

4. A door stop comprising a bracket channeled in cross section to form a guide, an up-turned end made on the bracket, an angle plate slidably confined in the guide of the 50 bracket, and a clamp screw arranged to clamp the angle plate to the bracket, the bracket at the end opposite the upturned end being apertured for pivotal mounting upon the floor.

5. A door stop comprising a bracket channeled in cross section to form a guide, an up-turned end made on the bracket, said bracket being apertured near the other end, an angle plate slidably confined in the guide 60 of the bracket, a clamp screw arranged to clamp the angle plate to the bracket, and a relatively wide face plate fastened to the angle plate to engage a door.

6. A door stop for the purposes stated, 65 comprising a bracket channeled in cross section to form a guide, and presenting a smooth flat bottom surface for contact with the floor, an up-turned end made on the bracket, an angle plate slidably confined in 70 the guide of the bracket, and a clamp screw arranged to clamp the angle plate to the bracket, and a face plate fastened to the angle plate to engage a door, and means related with the bracket to secure same to the 75 floor.

NATHANIEL CRANK.
